[57] ABSTRACT

Compositions of matter having two ring nuclei composed of 6 carbon atoms essentially superimposed in fixed parallel planes with respect to each other and process of preparing the same. The compositions may be advantageously employed in lubricating grease.

1 Claim, No Drawings

SANDWICH TYPE CHEMICAL COMPOUNDS

This is a division of application Ser. No. 521,256 filed Nov. 6, 1974, now U.S. Pat. No. 3,953,426 said application Ser. No. 521,256 being a divisional application of Ser. No. 359,126 filed May 10, 1973, now U.S. Pat. No. 3,860,610, said latter application being a continuation of application Ser. No. 68,047 filed Aug. 28, 1970, now abandoned, which latter application is a division of application Ser. No. 706,663 filed Feb. 19, 1968, now U.S. Pat. No. 3,597,431 which latter application is in turn a continuation-in-part of application Ser. No. 554,651 filed June 2, 1966, now abandoned.

This invention relates to new compositions of matter and methods of preparing the same.

The principal object of the invention is to prepare new chemical compounds having unique structure. The new compositions of the invention are chemicals having two ring nuclei composed of 6 carbon atoms essentially superimposed in fixed parallel planes with respect to each other. Unlike chain type polymer compounds, the compositions of the invention have a structure which can be characterized as "sandwich type" with the ring nuclei being essentially superimposed with respect to each other.

The new compositions of the invention are prepared by reacting substantially equal molar quantities of reactant A with reactant B in the presence of a solvent such as, for example, dimethylformamide, tetramethylene sulfone, water, ethanol, carbon tetrachloride and the like. In a preferred embodiment compounds reactive with alcohols or mercaptans are employed in the reaction mixture to assist linking of the reactants. Representative of such linking agents are sodium hydroxide, sodium hydride, potassium hydroxide, sodium diethyl amide, sodium amide and the like. The reaction, depending upon the particular substituents of the reactants, is carried out at temperatures from about 0 to about 200° C., and generally 75° to 150° C.

The reaction scheme for preparation of the new compounds of the invention can be illustrated as follows utilizing reactants having a benzene ring nuclei as illustrative (however the saturation of the ring can vary and saturated 6 carbon member rings can be employed):

Y = (CH₂)_n,
Z = NR₂, SR, OH, (R=H or alkyl of 1-4 carbon atoms),
X = Cl, Br, I,
W = NR, S, O, NR₂⁺X⁻ or SR⁺X⁻ (R=H or alkyl of 1-4 carbon atoms).

When there are less than 6 Z-Y or X-Y groups present in the reactants the other substituents present in the ring nuclei are hydrogen, alkyl, hydroxyl, methoxy, halogens and like substituents which do not interfere with the desired reaction.

As will be apparent from the above, reaction scheme W in certain instances represents ammonium or sulfonium salts. It is within the scope of the present invention to react three Z-Y groups with six X-Y groups to give a reaction product with six connections to one ring nucleus and three connections to the other ring nucleus and to isolate ammonium or sulfonium salts or amines therefrom, in which case the end product will have the formula indicated below with

The following examples are illustrative of the present invention:

EXAMPLE I

Approximately 7.5 grams of hexabromomethylbenzene (Reactant B) are added to 100 milliliters of the solvent, tetramethylene sulfone. This mixture is heated to a temperature of approximately 140° C. and while maintaining this temperature approximately 3.3 grams of tri-(dimethylaminomethyl)phenol (Reactant A) are added. Heating is continued for 15-20 minutes. The reaction product is recovered by filtering the reaction mixture. The reaction is illustrated by the following

In the above formulae double bonds are indicated by heavy lines and each of the Reactants A and B can have from 3 to 6Z-Y and X-Y groups respectively with

scheme:

The reaction product is a solid which decomposes at temperatures above 200° C. and is soluble in water and insoluble in ethanol.

Analysis, Calculated for $C_{24}H_{30}N_3OBr_3 \cdot 4H_2O$: C, 41.9; H, 5.5; N, 6.1; Br, 34.9. Found: C, 41.7; H, 6.5; N, 6.2; Br, 32.6

EXAMPLE II

Five grams of the reaction product of Example I and 50 milliliters of triethylamine in 150 milliliters of absolute alcohol were refluxed for 2 hours. Then solvents were evaporated and the residue was washed with water. The molecular weight was determined on the resulting product having the formula shown below on a vapor pressure osmometer.

25

Calculated for $C_{21}H_{21}N_3O$: MW 331. Found: MW 348.

EXAMPLE III

In this example a reaction as follows was carried out:

65 In carrying out the reaction depicted above a warm solution (50°-70° C.) of 1.620 grams of reactant A in 70 milliliters of carbon tetrachloride was filtered and treated with a solution of 0.8 grams of sodium hydrox-

ide in 1 milliliter of water and 20 milliliters of ethanol. A warm solution (50°-70° C.) of 2.342 grams of reactant B dissolved in 50 milliliters of carbon tetrachloride was added and the mixture was refluxed 7 hours. The mixture was separated by filtration and the residue extracted successively with 75 milliliters of carbon tetrachloride and 75 milliliters water. The residue (1.7 grams) was dried one hour at 110° C. The product did not melt below 300° C.

Analyses calculated for $C_{18}H_{12}Cl_6S_3$:

	C	H	Cl	S
Theory	40.22	2.23	39.66	17.88
Found	38.99	2.43	39.66	16.79

Reactant B involved in the above synthesis can be prepared by the method of Ross et al. as described in the *Journal of Organic Chemistry*, Vol. 25, page 2102, 1960.

Reactant A can be prepared from reactant B by converting the latter to a Bunte salt followed by acid hydrolysis. An example of this procedure is as follows:

A mixture of 2.3 grams of compound B, 3.7 grams of sodium thiosulfate pentahydrate, 25 milliliters water, and 25 milliliters ethanol was stirred approximately 4 hours. A homogenous solution was formed during the first 2 hours. The solution was treated with 5 milliliters concentrated hydrochloric acid and the mixture was refluxed 1 hour. The mixture was cooled and filtered. The product was recrystallized from ethanol yielding 0.85 grams of reactant A melting at 155° C.

EXAMPLE IV

In this example a reaction was carried out as follows:

One gram of potassium hydroxide dissolved in 5 milliliters of 70% ethyl alcohol (30% water) was added to 1.51 grams of reactant A dissolved in carbon tetrachloride. This was reacted with 1.54 grams of reactant B dissolved in carbon tetrachloride at 50°-70° C. The reactant mixture was refluxed for 30 minutes. The mixture was separated by filtration and the residue

extracted successively with hot carbon tetrachloride and deionized water. The residue was dried 1 hour at 110° C. One and two-tenth grams of a light yellow solid that did not melt below 300° C. was obtained.

Analyses calculated for $C_{18}H_{12}Br_3Cl_3S_3$:

	C	H	Br	Cl	S
Theory	32.2	1.8	35.8	15.9	14.3
Found	31.3	1.97	35.8	16.1	14.3

Reactant A was obtained as follows:

2,4,6 Tribromomesitylene [G. F. Hennion et al., J. Amer. Chem. Soc. Vol. 68, page 424 (1946)] was brominated as follows:

A boiling solution of 63 grams 2,4,6 tribromomesitylene in 350 milliliters carbon tetrachloride was irradiated with a 200-watt tungsten lamp and treated dropwise with 40 milliliters bromine during seven hours. The mixture was refluxed 15 hours, cooled, and filtered to give 22.1 grams 2,4,6 tribromo 1,3,5 tri (bromomethyl) benzene, melting at 220°-223° C.

Analysis calculated for $C_9H_6Br_6$:

	Br
Theory	80.78
Found	80.77

A mixture of 8.92 grams 2,4,6 tribromo - 1,3,5 tri (bromomethyl) benzene, 11.1 grams sodium thiosulfate pentahydrate, 75 milliliters ethanol and 75 milliliters water was stirred at 50°-60° C. for seven hours and then at room temperature for 16 hours. The resultant solution was treated with 15 milliliters concen-

trated hydrochloric acid and this solution was refluxed 1.5 hours. The product reactant A, which was obtained by filtration in 4.7 grams yield, melted at 200° C.

Analysis calculated for $C_9H_6Br_3S_3$:

	C	H
Theory	23.86	2.00
Found	23.75	1.98

added and the mixture was heated 2½ hours at 70°–76° C. The mixture was cooled and filtered. The residue was washed with hot deionized water and hot carbon tetrachloride to give a solid product which did not melt below 300° C.

Analyses calculated for $C_{18}H_{12}Cl_6O_3$:

	C	H	Cl	O
Theory	44.2	2.4	43.6	9.8
Found	43.76	3.48	43.12	9.92

EXAMPLE V

In this example a reaction was carried out as follows:

In carrying out the above reaction a suspension of 0.55 grams of 51% sodium hydride in mineral oil in 60 milliliters diethylamine was stirred and heated until the sodium hydride had disappeared and a gelatinous precipitate separated. Then 1.01 grams of reactant A and 100 milliliters carbon tetrachloride was added. The mixture was distilled with addition of fresh carbon tetrachloride until the boiling point reached 76° C. (727 milliliters). Reactant B (1.8 grams) was then

Reactant A was prepared by the method of Ross et al., Journal of Organic Chemistry, Vol. 25, page 2104 – 1960.

EXAMPLE VI

In this example a reaction was carried out as follows:

-continued

In carrying out the above reaction 3.0 grams of reactant B were dissolved in carbon tetrachloride and the solution heated to boiling. To this solution was added 1.7 grams of reactant A (commercially available) dissolved in carbon tetrachloride. The reaction mixture was heated at a temperature of 65°-75° C. for 20 minutes. A white precipitate was formed which was filtered and washed with additional carbon tetrachloride then dried overnight in an oven at a temperature of 90° C. Two and one-tenth grams of product were obtained.

Analysis calculated for $C_{23}H_{30}N_3Cl_3Br_2O$:

	C	H	N	Br	Cl
Theory	43.74	4.75	6.66	25.35	16.96
Found	44.48	6.9	6.04	24.53	—

A reaction similar to the above was conducted at room temperature. Thus, 6.0 grams of compound B were reacted with 3.7 grams of compound A. The product was dried at room temperature; yield, 5.8 grams.

	C	H	N	Br	Cl
Found	42.28	6.05	7.26	22.32	14.02

The chlorine atoms in the product produced above are easily replaced even on standing in air or while heating in an oven.

The sandwich structure of the product produced as above described was confirmed by dissolving 12.2 grams of the product in 650 milliliters deionized water. An excess of triethyl amine (38 milliliters) was added and the mixture heated to 75° C. for 40 minutes to remove methyl bromide. The top layer was extracted with benzene, filtered, evaporated, and dried. The resi-

50
55

due was a viscous liquid. Analyses showed some of the chlorine was replaced.

Analyses calculated for $C_{21}H_{26}N_3Cl_2O_3$ (two chlorines replaced with two OH):

20

25

	MW	Cl
Theory	403	8.68
Found	395	11.33

The compositions embraced by this invention have various utility. Thus, for example, methyl ammonium salts can be advantageously employed as methylating agents. The "sandwich" compositions of the present invention containing sulfur, oxygen and nitrogen can be advantageously employed in lubricating greases to impart extreme pressure characteristics thereto.

Those modifications and equivalents which fall within the spirit of the invention and the scope of the appended claims are to be considered part of the invention.

We claim:

1. A new composition of matter having two ring nuclei composed of six carbon atoms essentially superimposed in fixed parallel planes with respect to each other and having the formula:

* * * * *

UNITED STATES PATENT OFFICE
CERTIFICATE OF CORRECTION

PATENT NO. : 4,018,795

DATED : April 19, 1977

INVENTOR(S) : EARL DAN FLICKINGER and CHARLES MERLYN BUESS

It is certified that error appears in the above-identified patent and that said Letters Patent are hereby corrected as shown below:

Double bonds should be indicated in the formulae in Columns 1 and 2 of the patent by a heavy vertical line on the right side of each 6-carbon ring and heavy diagonal lines on the left side of each 6-carbon ring.

Double bonds should be indicated in the formulae in Columns 3, 4, 5, 7, 8, 9 and 10 of the patent by a heavy vertical line on the left side of each 6-carbon ring and heavy diagonal lines on the right side of each 6-carbon ring.
